DEEP WELL PUMP

James M. Hait, Los Angeles, Calif., assignor to
 Food Machinery Corporation, San Jose, Calif.,
 a corporation of Delaware

Application January 9, 1939, Serial No. 249,963

2 Claims. (Cl. 103—119)

This invention relates to deep well pumps and has particular utility in pumping liquids from deep wells where said liquids contain a considerable amount of sediment held in suspension.

This situation is particularly prevalent in deep water wells where it has become the common practice to use rotary turbine pumps which are not subject to sanding up by the precipitation of sediment from the water in the pump tubing while the pump is halted. Turbine pumps, however, are not positive acting, and for excessive depths a positive acting pump is preferable to a pump depending on centrifugal action. One of the newest and most unique of positive acting pumps is that invented by Rene Joseph Louis Moineau and disclosed in his U. S. Letters Patent 1,892,217, 2,028,407 and 2,085,115. The Moineau type of pump, however, has not hitherto been adapted for use in deep wells because of the fact that the pump acts by the rotation of a rotor in the bore of a stator with such a relation of helical surfaces on the rotor and stator as to produce a series of closed pockets between these two elements which rise as one of the elements is rotated relatively to the other. There is always one and generally two of these pockets opening upwardly from the Moineau type of pump at all times during this operation. These pockets remain open, of course, whenever the pump is stopped. While the Moineau pump is capable of handling a liquid having sediment carried in suspension therein, it is rendered inoperative by those pockets opening at the discharge end of the pump being filled with sedimentary material. Prior to my present invention, therefore, this type of pump has not been available for use in deep wells.

It is an object of my invention to make the Moineau pump available for deep well use by preventing this pump from being sand-locked by the precipitation of sediment in the upwardly open pockets of the pump when the pump is temporarily shut down.

The manner of accomplishing the foregoing object as well as further objects and advantages will be made manifest in the following description taken in connection with the accompanying drawings, in which

Fig. 1 is a diagrammatic vertical sectional view of a deep well pump installation of a Moineau type pump incorporating a preferred embodiment of the present invention.

Fig. 2 is an enlarged fragmentary view taken on the line 2—2 of Fig. 1 and illustrating in detail the preferred design of the sand traps of this invention.

Fig. 3 is a cross sectional view taken on the line 3—3 of Fig. 2.

Fig. 4 is a cross sectional view taken on the line 4—4 of Fig. 2.

Fig. 5 is an operation view on reduced scale illustrating the pump installation shown in Fig. 1 while operating.

Fig. 6 is a view similar to Fig. 5 showing the situation which prevails when the pump is temporarily shut down and the sedimentary matter has precipitated from the water in the pump tubing.

Fig. 7 is an enlarged cross sectional view taken on the line 7—7 of Fig. 5 and illustrating the manner in which the bell flange or cup portion of the preferred form of sand trap of this invention collapses under the pressure of water flowing from the pump and up the pump tubing.

Fig. 8 is a fragmentary section of a pump tubing illustrating a modified form of the sand trap of this invention.

Fig. 9 is a cross sectional view taken on the line 9—9 of Fig. 8.

Fig. 10 is a view similar to Fig. 8 and showing the condition which prevails when the pump is temporarily halted.

Fig. 11 is a view similar to Fig. 8 illustrating a second modified form of the sand trap of this invention in the condition which prevails during the operation of the pump.

Fig. 12 is a cross sectional view taken on the line 12—12 of Fig. 11.

Fig. 13 is a cross sectional view taken on the line 13—13 of Fig. 11.

Fig. 14 is a view similar to Fig. 11 illustrating the situation which prevails when the operation of the pump is temporarily suspended.

Fig. 15 is a diagrammatic vertical sectional view showing a modified form of installation of a Moineau pump with the latter operated by a submersible motor and incorporating the preferred form of sand traps of the present invention.

Referring specifically to the drawings, it will be seen that the present invention is embodied in the deep well pumping apparatus 20 which is installed in a deep well 21.

The well 21 has a casing 22 and supported on a concrete foundation 23 at the top of this is a power head 24 embodying an electric motor which has suitable connection with a line shaft 26 extending downwardly into the well from the power head 24. The power head provides a passage 30 for the discharge of liquid pumped from the well 21. Disposed inside the casing 22 and screwed into the lower end of the power head

24 so as to connect with the passage 30 is a pump tubing 31 which is made in sections 32 joined by pipe couplings 33. The line shaft 26 has bearings 35, each of which preferably includes a shell 36 enclosing a bushing 37 and a spider 38 formed on the shell 36, the spider having a ring 39 fitting closely within the tubing 31 and having an annular rib 40 which is disposed between adjacent ends of adjacent sections 32 of the tubing 31 so that each of the bearings 35 is rigidly united with the tubing 31 when the latter is assembled.

Connected to the lower end of the pump tubing 31 by a pipe coupling 45 is a tubing section 46, while joined to the lower end of the pipe section 46 by a pipe coupling 47 is a foot valve and strainer 48. Secured between the adjacent ends of the tubular elements joined by the pipe collars 45 and 47 are rings 49 which serve to position a stator 59 of a Moineau pump 60 within the tubing section 46.

The foot valve and strainer 48 has a tubular body 61 at the lower end of which is provided a valve seat 62 which connects with a strainer 63. Resting on the seat 62 is a foot valve 64, the stem 65 of which is guided in the end of the strainer 63.

While the stator 59 may be of any suitable type capable of cooperating with an internal rotor to pump liquid upwardly by producing upwardly traveling pockets, this stator is preferably of the Moineau type as shown in Moineau Patent No. 2,028,407, issued January 21, 1936. This stator, as shown in Fig. 1, includes a metal sleeve 70, to the interior surface of which is vulcanized a rubber stator body 71 having a bore 72. In the embodiment illustrated, the stator bore 72 has a left hand double pitched female thread formed therein. Thus, the inner surface of the stator bore 72 is generated by two discs disposed eccentrically on opposite sides of the axis of the stator and then rotated through a helical path about the axis of the stator.

Disposed in the stator bore 72 is a rotor 75 which is connected by a flexible coupling to an oscillatory link 77, the upper end of which is in turn connected by a flexible coupling 78, to the lower end of the line shaft 26. The rotor 75 is a single pitch left handed screw which is generated by a single disc traveling in a helical path about the axis of the screw. The pitch, or distance traveled by this disc along the axis of the rotor for each gyration of said disc about said axis is one-half the distance followed by the two discs for each gyration the latter makes about the axis of the stator in generating the helical surface of the stator bore 72. Thus it is seen that the relation between the pitch distance of the rotor and the pitch distance of the stator is the same as the relation between the number of threads in the helical surfaces of these elements. This is an essential condition of the Moineau type of pump which, when the stator and rotor are longer than a single pitch distance of the stator, causes to be produced by relative relation between the stator and rotor, a series of pockets which travel longitudinally along the stator bore 72. When the rotor 75 is rotated in an anti-clockwise direction in the stator 59, these pockets rise and produce a positive pumping action. The couplings 76 and 78 are substantially alike, each of these having a torque impeller 80 which is screwed on left hand threads on one end of the link 77 against one of the shoulders 81 provided on said link. Surrounding each of the torque 75

impellers 80 is a body of rubber 82 which is enclosed in a cap 83, the latter being screwed onto a base nut 84 in the case of the coupling 76. The base nut 84 is provided with a threaded bore 5 which screws onto a threaded stud 85 provided on the upper end of the rotor 75. In the case of the coupling 78 the cap 83 screws into a base nut 87 which is provided with a threaded bore into which the threaded lower end of the line shaft 26 10 screws so as to bring this nut against a shoulder 89 on said shaft.

The apparatus 20 also preferably includes two sand traps 90 and 91, the first of which is located about the line shaft 26 just above the lowermost 15 of the line shaft bearings 35. The sand trap 90 has a flexible rubber cup member 92 which includes an annular body 93 which snugly surrounds the shaft 26 and is held in a fixed vertical position on the shaft 26 by set collars 94 and 20 95. Extending upwardly and outwardly from the body 93 is a very flexible flange 96, the rim of which engages the inner face of the pump tubing 31 when the rubber cup member 92 is free from distorting forces.

25 The sand trap 91 is similar to the sand trap 90 and comprises a rubber cup member 97 having a body 98 which is fixed on the oscillating link 77 by set collars 99 and 100. Extending upwardly and outwardly from the rubber body 98 is an annular rubber flange 101, the upper end of which, when undistorted, is of such a diameter as to extend substantially into contact with the inner face of the pump tubing 31 even though the axis of the link 77 where the sand trap 91 is mounted 30 thereon is slightly eccentric with the axis of the pump tubing.

Operation

The apparatus 20 preferably operates in the following manner:

40 In the installation of this apparatus, the foot valve and strainer 48 is disposed beneath the surface of the liquid in the well 21 so that when the motor 25 is energized and the line shaft 26 rotates rapidly, this rotation is transmitted 45 through the couplings 78 and 76 and the oscillatory links 77 to the rotor 75 so that the latter rotates in a counterclockwise direction in the stator bore 72. As previously explained, this causes 50 a series of pockets 105 formed between the rotor 75 and the stator 59 to travel upwardly so as to evacuate air from the housing 61 of the foot valve 48 and draw liquid upwardly into the pump 60 and discharge this liquid into the lower end of 55 the pump tubing 31 to cause it to flow upwardly through this and out through the power head passage 39 into a pipe 110 connected with the discharge mouth of this passage.

The Moineau pump 60 is adapted for handling 60 liquids containing sedimentary material suspended therein, but prior to this invention the Moineau pump has been used entirely in horizontal position to avoid this pump being locked by the settling of this sediment into the pockets 65 105 which are open at the discharge end of the pump when the latter is halted. The present invention renders it possible to use this type of pump in a vertical installation for the purpose of pumping sediment-bearing liquids upwardly substantial distances above the pump without the pump being incapacitated when temporarily halted by the sediments dropping down into the aforesaid pockets and thus locking the rotor 75 against rotation in the stator 59.

70 When the motor 25 is shut off during pumping

operations, the line shaft 26 and the other elements connected thereto cease rotation so that the upward flow of liquid in the tubing 31 stops. The pump 60 and foot valve 64 obstruct the downward escape of liquid from the tubing 31 so that the tubing remains filled with liquid. The sediment suspended in this liquid, of course, immediately starts to settle and if the pump is allowed to remain idle for more than a few minutes all this sediment is deposited at the lower end of the body of liquid containing it. In the apparatus 20, the pump 60 may be located anywhere from a few feet to many hundred feet below the power head 24 so that even where there is no more than 1 per cent of suspended matter in the liquid pumped, this amount, when entirely deposited downwardly, may constitute a considerable quantity of solid matter. While the pump 60 is being operated, the upward flow of liquid discharged therefrom into the tubing 31 collapses the rubber cups 92 and 97 as shown by the full lines in Fig. 7 and by the dotted lines in Fig. 2. These cups are so flexible that they collapse in this manner without making any substantial resistance to the upward flow of liquid through the tubing 31. As soon as the apparatus is shut down, however, these cups return to their normal shape as shown in Fig. 2 in which the upper rim contacts the inner surface of the tubing 31 at two vertically spaced points disposed just above the pump 60. The free upward flow of the liquid when the pump 60 is in operation is clearly illustrated in Fig. 5, and Fig. 6 shows the result of shutting down the apparatus after the sediment suspended in the liquid in the pump tubing 31 is all settled downwardly. Here it is seen that the sand trap 90 has caught the bulk of the sediment settling out of this liquid while the sediment settling out between the sand trap 90 and the sand trap 91 is caught in the latter. By virtue of this arrangement, the sediment is practically entirely kept out of the pockets 105 of the pump 60 which open upwardly when the operation of the pump is halted. Thus, when the motor 25 is again started there is no abnormal resistance to the rotation of the rotor 75 in the stator 59 and the pump immediately recommences the discharge of liquid upwardly into the tubing 31. This flow of liquid creates a pressure just below the sand traps 90 and 91 so as to collapse the cups slightly so that this upwardly flowing liquid jetties the sediment deposited in these sand traps from the position in which it is deposited as shown in Fig. 6. The sediment is thus returned to a condition of suspension in the upward flowing stream of liquid in the tubing 31, thereby permitting the flexible cups 92 and 97 to be collapsed as shown in Fig. 7 and thus offer a minimum of resistance to the upward flow of liquid through the tubing 31.

While the lower end of the link 77 oscillates eccentrically about the axis of the tubing 31, the actual eccentricity is of such a slight degree as not to prevent the cup 97 from effectively trapping the sediment precipitated downwardly from the liquid in the tubing 31 below the sand trap 90.

Reference is now made to Figs. 8, 9 and 10 of the drawings in which I have shown a modified form of sand trap 110 of my invention, the latter including an upper, funnel-shaped member 111 and a lower, cup-shaped member 112. The upper member includes an annular ring 114 mounted between sections 32 of the pump tubing 31. Formed integral with and extending down-

ward from the ring 114 of the member 111 is an annular nipple 115. The lower member 112 includes a collar portion 117 fixed on the link 77 by a set screw 118. Formed integral with the collar 117 is a cup 119, the upper portion of which overlaps the lower portion of the nipple 115 of the upper member 111 to provide an annular space 120.

In practice, the sand trap 110 may be used in place of either one or both of the sand traps 90 and 91 shown in Fig. 1 and for the purpose of illustration shown positioned on the link 77 between the aforescribed couplings 76 and 78, it being necessary to provide a joint in the tubing 31 at the location of the sand trap 110 as shown in Fig. 8.

The annular space 120 between the cup 119 and nipple 115 permits the aforescribed eccentric movement of the member 112 in relation to the stationary member 111, this space also permitting the flow of water through the sand trap 110 in the direction indicated by the arrows in Fig. 8.

When the pump 60 is stopped, the sediment which settles from the column of water above the sand trap 110 passes through the nipple 115 of the upper member 111 into the lower member 112. When the member 112 is filled to the level of the lower extremity of the nipple 115, as indicated by the line A—A of Fig. 10, further filling of the cup 119 is prevented by the nipple 115. After the cup 119 is filled, additional sediment is retained above the sand trap 110 as shown in Fig. 10 and the pump 60 is thus protected from being locked by sediment, as aforescribed. When the pump 60 is again started, the pressure below the sand trap 110 increases until the fluid forces its way through the body of sediment retained by the trap 110 and the flow soon washes all of the sediment from the sand trap.

Referring now to Figs. 11 to 14 inclusive, I have shown therein another modified form of sand trap 125 of my invention. The trap 125 includes a ring 128 disposed within the pump tubing 31. Formed integral with the ring 128 is a flange 129, the latter being locked between adjacent ends of sections 32 of the pump tubing 31. Supported concentrically within the ring 128 by a spider 130 is a housing 131 in which a bearing 132 is mounted, the latter receiving the line shaft 26. Formed on upper extremities of the ring 128 and housing 131 are annular valve seats 134 and 135 respectively. Threaded onto the ring 128 is a lift valve retaining cage 136, the latter containing an annular lift valve 137.

When used in the pumping apparatus 20 of my invention, the sand trap 125 is preferably installed in place of the bearing 35 and the sand trap 90 shown in Fig. 1. During operation of the pump 60, the liquid flows through the sand trap

125 in the direction indicated by the arrows of Fig. 11, the valve 137 being raised by the flow of liquid to the position in which it is shown in Fig. 11. When the pump 60 is stopped, the valve 137 drops onto the valve seats 134 and 135 thus sealing the pump tubing 31 at the level of the valve and preventing sediment from settling beyond the sand trap 125 as shown in Fig. 14, thus preventing the pump 60 from becoming sand-locked in the manner aforescribed. In order to protect the pump 60 from the small quantity of sediment which might settle into the pump from the liquid trapped between the pump 60 and the sand trap 125, the sand trap 91 may be used on the link 77 as shown in Fig. 1 to sup-

plement the sand trap 125 as an added precaution.

Reference is now made to Fig. 15 of the drawings in which a modified form of deep well pumping apparatus 140 of my invention is shown, similar parts in the apparatus 20 and 140 being indicated by similar reference numerals with primes added to the numerals used to indicate similar parts of the apparatus 140. Provided at the mouth of a deep well 21' is an elbow 145 in which an uppermost section 32' of a pump tubing 31' is threaded. Mounted on the lower end of the tubing 31' is a pump 60' which is identical to the aforescribed pump 60. Supported within the tubing 31' above the pump 60' by suitable spiders 147 is a submersible electric motor 148, the latter being connected to the pump 60' by flexible couplings 76', 78', and a link 77'. Electric current is supplied to the motor 148 by a cable 149 which extends upward through the tubing 31' and elbow 145 to a suitable supply of current.

To protect the pump 60' from sediment, a sand trap 152 is mounted on top of the motor 148. The trap 152 is similar in construction and operation to the aforescribed sand trap 90 of the apparatus 20 except that the trap 152 is mounted on the motor 148 instead of on the shaft 26 as shown in Fig. 1. To supplement the sand trap 152, a trap 91' is mounted on the link 77' as shown.

When the pump 60' is driven by the motor 148, the pumped liquid flows by the sand trap 91', through the spiders 147 and past the sand trap 152, the traps 91' and 152 being collapsed by the liquid as aforescribed. When the pump 60' is stopped, the sand traps 152 and 91' expand to the positions in which they are shown in Fig. 15 so as to trap any sediment which may settle from the liquid standing in the tubing 31' and thus prevent the pump 60' from becoming sand-locked.

Although I have shown and described but one preferred and several modified forms of deep well pumping apparatus of my invention, it is understood that other modifications and changes might be made therein without departing from the spirit of the invention or the scope of the appended claims.

I claim:

1. In a deep well pump, the combination of:

5 a pump tubing descending in said well from the top thereof to a pumping level therein; a pump provided at the lower end of said tubing and connected therewith; a shaft journalled within said tubing near the lower end thereof; means for rotating said shaft to drive said pump to pump well liquid upwardly through said tubing and about said shaft; and a rotary sand trap fixed on said shaft above said pump, said sand trap rotating with said shaft and comprising a hub snugly fitting said shaft, means for fixing said hub to said shaft, and a very flexible flange formed upon said hub and extending upwardly at a shallow angle into contact with the inner wall of said tubing, said flange being of such light weight and of such a flexible character as to readily collapse inwardly, while said shaft is rotating, to permit passage of well liquid upwardly through said tubing and past said sand trap, said flange, 10 however, having sufficient resilience, when rotation of said shaft ceases, to expand outwardly into annular contact with said tubing so as to catch particles of sand deposited from liquid in said tubing above said trap.

2. In a deep well pump, the combination of: 15 a pump tubing descending in said well from the top thereof to a pumping level therein; a rotary pump stator provided at the lower end of said tubing and connected therewith; a rotor disposed in said stator and adapted to gyrate therein about a vertical axis to pump liquid upwardly through said tubing; a shaft journalled within said tubing near the lower end thereof; a gyrating link connecting said shaft with said rotor; 20 means for rotating said shaft to cause the gyration of said rotor in said stator as aforesaid; and a sand trap provided on said link and comprising hub means fixed on said link, and a very flexible flange extending upwardly and outwardly 25 from said hub means so that no matter in what position said link is halted said flange expands to form an annular line of contact between said flange and said pump tubing a substantial distance above the union of said flange with said hub means, said flange being of sufficient flexibility to collapse readily in response to the upward flow of liquid through said tubing produced by said pump during the gyration of said link in driving said rotor.

50 JAMES M. HAIT.
